UNITED STATES PATENT OFFICE.

ALVIN HUNSICKER, OF WEEHAWKEN, NEW JERSEY, ASSIGNOR TO STANDARD OIL CLOTH CO., OF NEW YORK, N. Y.

DESIGN FOR OIL-CLOTH.

No. 39,297.

Specification for Design.

Patented May 5, 1908.

Application filed March 3, 1908. Serial No. 419,062. Term of patent 7 years.

To all whom it may concern:

Be it known that I, ALVIN HUNSICKER, a citizen of the United States, residing at Weehawken, in the county of Hudson and State of New Jersey, have invented a new, original, and ornamental Design for Oil - Cloth, of which the following is a specification, reference being had to the accompanying drawing, forming part thereof.

The figure is a plan view of a section of oil-cloth, showing my new design.

I claim:

The ornamental design for oilcloth, as shown.

ALVIN HUNSICKER.
